STRICKLING MACHINE

Odon Ghislain Joseph Meunier,
Fayt-lez-Manage, BelgiumApplication June 30, 1947, Serial No. 757,959
In Belgium December 14, 1942Section 1, Public Law 690, August 8, 1946
Patent expires December 14, 1962

1 Claim. (Cl. 22—24)

1

My invention relates to a strickling machine that, while allowing a highly accurate strickling, reduces considerably the duration of said operation.

The casting with a gig is applicable to parts of revolution of a sufficiently large size such as wheels, flywheels, bells and the like by means of a gig or strickle with a well-defined outline, that is caused to rotate inside the sand round the axis of revolution of the part to be cast.

Generally speaking the strickling is performed by hand, by means of more or less primitive instruments, directly on the ground of the foundry in the casting hall or else in a casting box.

Bells are preferably cast inside a pit on a masonry foundation serving as a core and allowing ramming the thickness piece that is cast with a hand gig and the like primitive tools.

Consequently, the strickling up to this day is a delicate operation that requires a comparatively long time and also skilled workmanship, without providing however a high accuracy, the tools available being only primitive instruments that do not allow any accurate work, and requiring considerable complications in the case of eccentric strickling for instance.

My invention has for its object to remove these various drawbacks and consists chiefly in that a mechanical control gives the tool carrying spindle and socket a continuus rotary movement around a vertical axis so that it is brought gradually and automatically to the desired height while it is also displaced as desired in a horizontal plane with a view to eccentric strickling, means being provided to this purpose first for ensuring a continuous rotary movement for said spindle, then for ensuring the vertical displacements of the latter and lastly for bringing the strickling tools eccentrically into their first operative position.

The vertical displacements of the spindle are produced through the association of two gears one of which is automatic and provides for rapid operation through a displacement of the whole driving mechanism with its carrier through a power control while the other provides a differential progression for the accuracy adjustment through a sliding of a member including bearings for the axis of the tool spindle and is controlled by hand.

In accompanying drawings is illustrated by way of example a form of execution of my invention. In said drawings:

Fig. 1 is an elevational view of a strickling machine according to the invention.

Fig. 2 is a cross-section through line I—I of Fig. 1.

2

Fig. 3 is a plan view of the strickling machine. Fig. 4 is a cross section through line II—II of Fig. 1.

In the form of execution illustrated in the drawings, the strickling machine includes a frame comprising a stand 1 with four arms, carrying an upright 2.

A slideway carrier 3 is freely and rotatably mounted on the upright 2 and its rotation is made easier through the interposition of one or more ball bearings.

The slideway carrier 3 is rigid with a dove-tail shaped slideway 4 and also with a bearing 5. On said slideway carrier may move vertically a cross-beam 6 forming a frame and to which is secured a motor 7 transmitting its rotary movement to a shaft 10 through the agency of the pinions 3—8¹—8²—8³—8⁴ and of a speed reducer 9. The disconnection of the shaft 10 with reference to the speed reducer 9 is ensured through a clutch 11.

The shaft 10 extends between the clutch 11 and the remote end of the cross beam 6. It carries slidingly two auxiliary clutch components 12 and 12' that are adapted to engage cooperating clutch components rigid with the corresponding pinions 13 and 13' so that the selective sliding of each clutch component 12 or 12' provides for the rotation in the corresponding direction of the pinion 14 in permanent mesh with both pinions 13 and 13'.

The pinion 14 is mounted on a shaft 15 that has its bearings inside the transmission box 16 secured to the slideway carrier 3; on the shaft 15 is provided a groove allowing the drive through the agency of a key of a toothed wheel 17 housed inside the box 16.

A gearwheel 18 rotating around a spindle housed inside the box 16 is driven by the toothed wheel 17 through the agency of the pinion 17¹. The gearwheel 18 is rigid with a threaded rod 19 that has its bearings inside the box 16 on one hand and inside the bearing 5 provided to said purpose on the other hand.

The worm 19 is screwed inside the cross-member 6 whereby, according to the direction of rotation of the worm 19, said cross-member 6 is urged in an upward or downward movement along the slideway carrier 3; in order to prevent the cross-member 6 from rotating with the slideway carrier 3 around the upright 2 of the frame, there is provided a catch piece 20 pivotally secured to said upright 2 and that may be housed inside one of the grooves 21 provided on the upper edge of the slideway carrier.

To the shaft 18 rotating freely inside the bearings 22 is secured a worm 23 meshing with a

helical gearwheel with a concave system of teeth 24 that slides through the agency of a key for instance, along a groove provided for this purpose in a tool-carrying shaft 25 whereby said shaft 25 may move vertically while remaining in engagement with the wheel provided with the concave set of teeth 24.

The tool carrying shaft is held in the bearings 26—26¹ provided in a slider 27 that may move vertically in a slide-way 28 assuming a dove tail shape and provided on a carriage 29.

The carriage 29 rests on the upper surface of the cross-member 6 through the agency of guiding members 30—31 so as to be capable of moving longitudinally with reference to said cross-member under the action of a threaded spindle 32 controlled by a hand-wheel 33 and that has its bearings 34 inside said cross-member 6.

Inside the slider 27 may rotate a threaded shaft 35 to which is screwed a bevel gear-wheel 36 that is held against the cross member 6 so that, at the moment of the operation of a hand wheel 37 rigid with the bevel gear 38 which is constantly in mesh with the gear wheel 36, the slider may move vertically inside the carriage.

To the lower end of the tool carrying shaft 25 is secured the tool carrying spindle 39 with two flanges inside which are provided openings 40 for securing the strickling tool or tools, the strickling boards and the like.

Through the operation of one of the clutches 12—12¹, it is possible to raise or to lower the frame cross-member 6 so as to bring progressively the tool to the desired level and also to raise it once the strickling is at an end. Preferably and with a view to obtaining a maximum accuracy, the tool will be lowered up to a few millimeters from the desired level and the final adjustment of the downward movement of the tool will be performed through the hand-wheel 37; thus the slider 27 is urged downwards and carries along with it the tool carrying shaft 25.

To make the adjustment easier, the upper part of the tool carrying shaft 25 carries a scale whereby it is possible while controlling the hand-wheel 37 to follow the downward movement of the tool with a very high accuracy without requiring measurements that are often intricate and require much time.

When it is desired to execute a strickling around vertical axes at variable distances from the axis of the slideway carrier 3, that is to say when it is desired to provide for strickling operations that are eccentric with reference to one another, it is sufficient to shift the carriage 29 by actuating the handwheel 33 controlling the threaded spindle 32 acting on the radial location of said carriage. In order to make it easier to measure the shifting to be given to the tool, the cross-member carries a scale in front of which may move a mark rigid with the carriage; it is thus possible to provide for a direct reading of the eccentricity given to the tool.

It may occur that a certain play arises between the different members controlling the slider and possibly that wear appears between the slider and its carriage and to this end there is provided a nut 41 screwed over this threaded shaft 35 and allowing the slider to be held fast at a predetermined operative height, on the carriage 29.

During the strickling operation it is necessary in most cases to define the location of various other parts of the mould that is to define the features of the part to be strickled; to this pur-

pose there is secured to the lower part of the carriage a protractor dial 42 subdivided into 360° in front of which may move a hand not illustrated secured for instance to the spindle 39.

Without any displacement of the strickling machine, being necessary, it is possible to execute several strickling operations; it is sufficient as a matter of fact to raise the catch 20 and to rotate the cross-member 6 through the desired angle; the cross-member will be held in the position given out by the housing of said catch in another groove 21 corresponding to the new position selected. In the drawings, there are provided four different positions at 90° for the cross-member but it should be understood that this number may vary according to the intended application and size of the strickling machine.

For the erection of the machine, there are provided two water gauges 43, 43¹ in a manner such that the cross-member may always be set in a truly horizontal position.

A form of execution of the invention has been thus described and illustrated by way of a mere indication and by no means as a limitation and obviously numerous modifications may be brought to its detail without widenning unduly its scope as defined in accompanying claim.

What I claim is:

In a strickling machine, the combination of a vertical independent upright, an undeformable rigid radial member fitted over said upright adapted to revolve unrestrictedly around same and provided with a longitudinal slideway, a strickling tool holding means including a vertical spindle portion, a socket rotatably carrying said spindle, a carrier for said socket adapted to slide in the longitudinal slideway of the radial member, a motor carried by the radial member near the rotary axis thereof, a horizontal shaft carried by the radial member and controlled by the motor, a vertical threaded rod rotatably carried by the tool socket, a gearwheel engaging said threaded rod and held permanently at an invariable level with reference to the radial member, hand-operated means controlling the angular setting of said gearwheel and thereby the vertical location of the tool socket with reference to said radial member, and control means for adjusting the longitudinal position of said carrier and consequently of the spindle and wormwheel on the slideway.

ODON GHISLAIN JOSEPH MEUNIER.
